UNITED STATES PATENT OFFICE.

HERMÓGENES LEÓN CEDEÑO, OF SANTIAGO, CUBA.

TALKING MACHINE.

Application filed September 15, 1927, Serial No. 219,795, and in Cuba May 10, 1927.

This invention relates to talking machines and has for its principal object the provision of improvements in the construction of machines of this type particularly with the end 5 in view of amplifying the sound waves with more fidelity to the original tones than is done in machines as constructed up to the present time.

The object of the invention involves amplifying the sound waves concurrently by a plurality of similar amplifying devices and then recomposing the amplified waves in order that spurious waves or distortions in tone incident to certain of the sound amplifying means will be damped or nullified by the bringing together of the amplified sounds from the several amplifying means so as to reproduce substantially identically 15 the tone of the original sound.

This object is obtained by means of a sound cabinet of the usual construction and dimensions in which is placed a plurality of trumpets for amplifying the sound separately and which are connected, two or more to a single horn whereby the separately amplified sounds are recomposed in the horn, it being desirable to provide a plurality of groups of trumpets and a number of horns corresponding to the number of the groups, to each of 20 which the horns of a group are connected.

Other objects of the invention will appear as the following description of an illustrative embodiment thereof proceeds.

In the drawings:

The Figure 1 is a perspective view of the device with the door of the cabinet of same appearing opened,

The Figure 2 is a front elevation which demonstrates separately and in detail a modification of the present invention.

The Figure 3 is a rear elevation, and

The Figure 4 is a vertical section according to lines 4—4 of the Figure 3.

Referring now in detail to the several figures the numeral 1 represents a cabinet of usual construction the upper part of which encloses the turntable 5, reproducer 6 and tone arm 4, as in usual constructions, the lower part constituting a sound or resonating 45 chamber.

Toward the front of this lower part or resonating chamber is secured a frame *a*, best shown in Figure 4, which supports and holds in place the novel amplifying and recomposing means constituting the present invention. 50 Connected to the frame *a* are horns

2 and 3. These have the general form of truncated pyramids flaring toward the front of the cabinet and having their small bases toward the rear. The dimensions of the horn 60 may conveniently follow the dimensions of the cabinet. In the present instance the horns are of greater width than height and one is placed immediately above the other, the front or flared ends of the horn terminating substantially in the front plane of the talking machine. 65

The small bases of the horns consist of panels 2' and 3' having apertures 12 preferably symmetrically arranged at the sides of 70 said bases and a central aperture 11. The horns thus constructed, constitute recomposing means for the sound waves, the latter being separately amplified by a plurality of trumpets 7 and 8. These trumpets are of 75 tapered form having their small ends communicating by means of apertures 10 with the lower end of the tone arm 4. The larger or flared ends of the trumpets are connected to the openings in the panels 2' and 3' of the 80 horns. The trumpets are all of the same length and since the horn 2 is above the horn 3 it is necessary to dispose of the length of the trumpets 7 which are connected to the horn 2 by bending or convolving them as 85 shown at 7'.

The operation of the invention will now be explained. Sounds emanating from the tone arm 4 are separately amplified in the trumpets 7 and 8. It is practically impossible to obtain mechanical amplification without at least some distortion or the producing of spurious vibrations which interfere with the purity of the delivered tone. However, such interfering factors being accidental, 90 they do not occur with the same vibration frequency or of the same quality or concurrently in each of the four trumpets. Consequently, when the four amplified sounds are again thrown together a new amplified tone 95 100 is recomposed in which the defects incidental to each individual amplification are damped or nullified by the beneficial interference produced by each of the amplified tones upon the others. 105

The recomposition takes place in the horns 2 and 3 where the composed sounds are further amplified and in fact the recomposition is completed just in front of the talking machine where the amplified and rectified tones 110 from all the horns mingle.

The central apertures 11 formed in the

panels 2' and 3' of the horns place the horns in communication with the enclosed air space within the cabinet of the talking machine, the resonating properties of which are thus made available.

It is evident that within the principles of constructions before mentioned there is room for other modifications, without departing from the spirit of the invention.

10 I claim:

1. In talking machines, the combination with a tone arm, of a plurality of trumpets of the same length, said trumpets being installed inside the tone chamber of the machine 15 and in communication with said tone arm, and a plurality of horns also within said tone chamber to each of which more than one of the trumpets is connected, for recomposing the sound separately amplified by the 20 trumpets and for further amplifying the same.

2. In talking machines, the combination with a tone arm, of a plurality of trumpets of the same length, said trumpets being installed inside the tone chamber of the machine 25 and in communication with said tone arm, and a plurality of horns also within said tone chamber to each of which more than one of the trumpets is connected, for recomposing the sound separately amplified by the 30 trumpet and for further amplifying the same, each horn being formed substantially as a truncated pyramid having a panel for its smaller base provided with apertures to 35 which the trumpets are connected.

3. A talking machine as claimed in claim 1, the said horns being formed as truncated pyramids each having a panel for its smaller base, a plurality of amplifying trumpets for each panel and apertures in said panel to 40 which said trumpets are connected, affording communication between said trumpets and said horns, said panels being each provided with an aperture placing said horns in communication with the resonating chamber of the cabinet of the talking machine. 45

4. In a talking machine a resonating cabinet and a tone arm, a plurality of trumpets in said cabinet connected at their smaller ends to said tone arm, said trumpets being 50 coordinated in groups and being of the same length, the trumpets of one group being convolved to dispose the mouths of said terminals above the mouths of the trumpets of the other group horns arranged in said 55 chamber one above the other, each horn having the general form of a truncated pyramid with the smaller base toward said trumpets, panels constituting the bases of said pyramids, said panels being provided 60 with apertures, the trumpets of each group being connected to the respective horns, through said apertures, said panels being provided with an additional aperture placing 65 said horns in direct communication with said resonating chamber.

In testimony whereof I have signed my name to this specification.

HERMÓGENES LEÓN CEDEÑO.
